Primary Examiner—Stella Reid*Assistant Examiner*—Mark Goodwin(74) *Attorney, Agent, or Firm*—Thomas, Kayden, Horstemeyer & Risley, LLP(57) **CLAIM**

The ornamental design for a digital wire wall plate, as shown and described.

DESCRIPTION

FIG. 1 is a front left side perspective view of the digital wire wall plate showing my new design, with the broken line showing of the cable in FIG. 1 forming no part of the claimed design;

FIG. 2 is a left side elevational view thereof, with the right side elevational view being a mirror image thereof;

FIG. 3 is a top view thereof;

FIG. 4 is a front elevational view thereof;

FIG. 5 is a bottom view thereof; and,

FIG. 6 is a back elevational view thereof.
